(57) **CLAIM**

The ornamental design for a coin counter as shown and described.

DESCRIPTION

FIG. 1 is a top, front perspective view of a coin counter showing my new design;

FIG. 2 is a back, bottom perspective view thereof;

FIG. 3 is a front view thereof;

FIG. 4 is a back view thereof;

FIG. 5 is a left view thereof;

FIG. 6 is a right view thereof;

FIG. 7 is a top plan view thereof; and,

FIG. 8 is a bottom plan view thereof.

The broken lines depict portions of the coin counter and form no part of the claimed design.

1 Claim, 8 Drawing Sheets(56)
